SHEET REGISTERING MECHANISM FOR
PRINTING MACHINESWilliam F. Huck, Richmond Hill, N. Y., assignor
to R. Hoe & Co., Inc., New York, N. Y., a corporation of New YorkApplication October 2, 1937, Serial No. 166,952
Renewed April 12, 1940

42 Claims. (Cl. 101—174)

This invention relates to multi-color sheet fed rotary printing machines and more particularly to a sheet feeding and registering mechanism for association and use with such machines whereby the sheets will be more conveniently, expeditiously and accurately registered and fed to the machine.

It is particularly desirable that the sheets be accurately registered upon a sheet carrying device before they are presented to the printing units of a multi-color printing machine, and to detect and strip from the sheet carrying device any sheets not properly registered. It is also desirable to provide means to actuate suitable printing cylinder control mechanism, to separate the cooperating cylinders of each printing unit, when a sheet has been so stripped from the sheet carrying device and the said device is passing the respective printing unit.

One object of this invention is to provide a sheet feeding mechanism whereby the above mentioned advantages will be obtained.

Another object is to provide in a sheet feeding mechanism a sheet receiving cylinder adapted to receive the sheets one at a time, and to locate them thereon in peripheral and axial register.

Another object is to provide means on a sheet receiving cylinder of the above nature to detect misplaced sheets and which is adapted to subsequently strip such sheets from the cylinder.

Still another object is to provide, in association with a sheet receiving cylinder of the above type, means to set a control means on a sheet gripping device, when no sheet is received thereby, in condition to actuate a printing cylinder tripping mechanism.

A further object is to provide a sheet receiving cylinder with means to hold the received sheet thereon and which is operable to locate the sheet axially thereon, while firmly holding it upon the periphery of the cylinder and maintaining it taut in an axial direction.

A still further object of this invention is to provide, in combination with a sheet receiving cylinder of the above nature, a sheet carrying mechanism including a flexible member having sheet grippers thereon and means to accurately register the sheet grippers with the operable parts of the sheet receiving cylinder.

It is also an object of this invention to provide a sheet feeding and registering mechanism of generally improved construction, whereby the same will be simple, durable, and inexpensive in

construction, as well as convenient, practical, serviceable and efficient in use.

With the foregoing and other objects in view, which will appear as the description proceeds, the invention resides in the combinations and arrangements of parts, and in the details of construction hereinafter described and claimed.

The preferred embodiment of the invention is illustrated in the accompanying drawings, where-

Figure 1 is a diagrammatic view of a multi-color printing machine with which the sheet feeding mechanism of this invention may be associated;

Figure 2 is a top plan view of a sheet receiving cylinder having the sheet feeding and registering mechanism of this invention associated therewith;

Figures 3, 4 and 5 are broken longitudinal sectional views of the cylinder shown in Figure 2, each section being a continuation of another. Certain parts are shown moved transversely from their true positions to more clearly show their longitudinal positions relatively to each other;

Figure 6 is a transverse section of the mechanism looking in the direction of the arrows 6 in Figure 2;

Figure 7 is an enlarged partial end view of the cylinder looking in the direction of the arrows 7 in Figure 3;

Figure 8 is an enlarged partial section looking in the direction of the arrows 8 in Figure 4;

Figure 9 is an enlarged partial transverse section of the cylinder looking in the direction of the arrows 9 in Figure 2;

Figure 10 is a transverse section of the mechanism looking in the direction of the arrows 10 in Figure 2;

Figure 11 is a transverse section of the sheet gripping device looking in the direction of the arrows 11 in Figure 3;

Figure 12 is an enlarged top plan view of one portion of the sheet holding device;

Figure 13 is a section on line 13—13 of Figure 12; and

Figure 14 is an underneath view of part of the sheet holding device looking in the direction of the arrows 14 in Figure 8.

The sheet feeding and registering mechanism illustrated in the drawings and which embodies the principles and novel features of this invention includes a conveyor and suitable guides to feed sheets one at a time to the sheet transfer or receiving cylinder, sheet engaging stops on the cylinder to peripherally locate and register the

- sheets as they are received, means to axially locate and register the sheets on the cylinder, including a stop plate and an air pressure actuated sheet holding device which is adapted to draw the sheets taut and hold them firmly upon the periphery of the cylinder, and a swingable finger adapted to detect the presence of a sheet improperly located. The drawings also illustrate a sheet gripping device, suitable means on the cylinder to locate and register the sheet gripping device, camming means to actuate the sheet gripping device to grip a sheet, cam means acting on the sheet gripping device to insure it being positively located by the locating and registering means, means actuated by the detecting fingers to release a sheet improperly located from the sheet gripping device and to strip it from the cylinder, and means to set a control member associated with the sheet gripping device and adapted to cause the printing cylinders to be tripped as the device is carried thereto by an endless conveyor chain or the like whereby actuation of the printing unit will be prevented when a sheet is not presented thereto. Suitable control and actuating means are also illustrated, whereby all of the above means and devices are actuated substantially automatically during the rotative movement of the cylinder and in timed relation to each other.
- 30 A printing machine, of the offset lithographic type, in which mechanism embodying the features of this invention is included, is illustrated diagrammatically in Figure 1. Herein a sheet supply 11 is shown from which sheets may be fed one at a time by a suitable sheet feeding device 12 to a sheet receiving and transfer cylinder 13 over which a plurality of sheet gripping devices are moved by spaced apart endless chains 14 and by which they are carried successively to the printing units 15, 16, 17 and 18, each of which may be adapted to print different colored impressions upon the sheets. Each of the printing units includes form and blanket cylinders 19 and 21, an impression cylinder 22, and suitable inking and dampening mechanisms 23 and 24 respectively. Each printing unit is also provided with a well known form of cylinder tripping mechanism indicated at 25 (in Figure 1), which is adapted to be actuated by the engagement of a part, herein constituted by a roller 26, (shown in Figures 2 and 3, extending from the conveyor chain 14 and disposed in advance of a sheet gripping device), with a control finger 27 forming part of the cylinder tripping mechanism of each printing unit. After passing through the printing units, the sheets are removed from the sheet gripping device and delivered to a suitable receiver 28, by a transfer belt or chain 29.
- 60 The sheet feeding device 12, illustrated in Figures 1 and 10, includes endless belts or tapes 31 running about suitable rollers 32 and 33 which are driven from a sheet separating device (not shown) but which is associated with the feeding device and with it is driven by the press drive. Chains (not shown) are provided, having spaced apart guiding members 40 thereon (see Figure 10), and these chains are arranged to be driven at a speed slightly less than the tapes 31 and to run parallel therewith. The purpose of the members 40 is to engage the front edge of the sheet separated from the pile 11 and maintain it square on the tapes 31. From the endless tapes 31, the sheets are directed onto a guide plate 41.
- 70 The guide plate 41 is adapted to direct the sheets upwardly and in under a plurality of end-

less belts or tapes 42, and between them and the cylinder 13. Both the tapes 31 and the tapes 42 are driven at surface speed slightly faster than the peripheral surface speed of the cylinder 13 whereby the forward edge of the sheets being fed is pushed firmly against a series of stops 43 (see Figures 3, 4, 5 and 9) extending outwardly from the periphery of the cylinder 13 and which are spaced apart at regular intervals lengthwise of the cylinder (see Figure 2). The tapes 42 are driven from the large gear 35 by the pinions 34 and 44 (see Figure 6) secured on the shafts of the rollers 45 and 47 respectively, over which the belts 42 are led. The large gear 35 is connected to the shaft 36 of the cylinder 13 which is driven from a vertical shaft 37 (see Figure 5) through bevel gears 38 and 39, the shaft 37 being understood to be drivingly connected to a common source of power for the printing units and driven in timed relation thereto.

20 The engagement of the forward edge of the sheet with the stops 43 locates each of the sheets on the cylinder 13 in a predetermined position on its periphery as they are fed thereto by the tapes 31; the tapes 42, due to running slightly faster than the cylinder firmly holding the sheets against the stops 43 after they have passed away from the influence of the pusher members 40.

25 A pair of oppositely directed and axially aligned bars 48 and 49 are slidably mounted between a pair of gibs 51 and 52 secured in a longitudinally directed slot provided in and extending the length of the cylinder 13 and suitably spaced rearwardly of the stops 43 in respect to the rotating direction of the cylinder 13 (see Figures 2, 12 and 13). 35 Each bar 48 and 49 is mounted upon and secured to a slide 53 which slides are slidably mounted, preferably on bearing balls 54, to and between the gibs 51 and 52 (see Figure 13). Each bar 48 and 49 extends with its slide 53 from a point 40 spaced inwardly from the adjacent cylinder end to a point spaced from the transverse center of the cylinder to permit it sliding in either direction, plates 55 being provided at each end of the slides 53 to retain the bearing balls 54 in place. 45

50 The bars 48 and 49 are each provided with a plurality of counterboard openings 56 in which spring pressed rotatable valve stems 57 are disposed. The valve stems 57 have an enlarged headed end 58 between which and the shoulder 59, formed by the counterbore portion of the opening 56, a coiled spring 61 reacts to maintain the head end 58 firmly against the upper surface of the slide 53. Each valve stem has a central bore 62 extending downwardly toward its headed end 58 and which is stopped short of the extreme lower end of the stem and is adapted to be connected to a longitudinally extending groove 63 formed in the slide 53 by an opening or port 64 angularly disposed in respect to the axis of the bore 62. A tool receiving slot 65 is provided in the upper end of each valve stem by which the respective stem may be rotated to connect or disconnect the opening 64 with the groove 63 in the slide 53.

55 The grooves 63, in each slide, terminate at the opposing ends of the slides 53 and have a tube 66 extending therefrom into a sleeve 67 (see Figure 4). The sleeve 67 is secured to an adjacent and centrally disposed cylinder part 72, herein comprising one of a plurality of axially spaced apart discs 68, 69, 71, 72, 73, 74 and 75, each secured on the shaft 36 and which support the outer shell 76 to form the cylinder 13. A bore 77 is provided in the disc 72 (see Figures 4 and 9) and leads 75

inwardly into connection with an opening 78 extending inwardly from a face of the disc. A base block 79 of a valve, secured to the face of the disc 72, is provided with a port 81 in connection with the opening 78 and with an arcuate recess 82 formed in the face of the block 79 adjacent the disc 72. Another arcuate recess 83 in opposed relation to the recess 82 is provided in the face of the block 79 adjacent the disc 72 and is suitably connected, as by a pipe 84 to a bore 85 formed in the cylinder shaft 36 (see Figure 3). The bore 85 is connected at an end of the shaft 36, herein shown as the left hand end to a vacuum pump (not shown) by a pipe 86.

15 Adjacent ends of the recesses 82 and 83 (see Figure 9) are connected to the upper surface of the block 79 by suitable openings 87 and 88 respectively and are adapted to be connected by rotation of a valve plate 89 (see Figure 4) rotatively mounted upon a stud 91 and pressed firmly against the block 79 by a spring 92. Recesses 93 and 94 provided in the face of the valve plate adjacent the block 79 are adapted to bridge the openings 87 and 88 to connect the recesses 82 and 25 83 whereby the vacuum pump (not shown) may be connected to the openings 62 in the stems 57 (see Figure 12), disposed in the bars 48 and 49, to cause the sheets to be firmly held on the cylinder in the position they have been located by the 30 stops 43.

An arm 95 (see Figures 9 and 10) is provided on the plate 89 and has a roller 96 journaled in its free end adapted to be engaged between the spaced portions of the bifurcated end of an arm 35 97. The arm 97 is secured to a rock shaft 98 which extends from its bearing in the disc 73 to and beyond the left hand end of the cylinder as viewed in Figures 3 and 4.

A arm 99 is secured upon the outer end of the 40 shaft 98 (see Figures 3 and 6). A roller 101 is journaled to the free end of the arm 99 and rides upon the periphery of a plate cam 102 whereby the rock shaft will be rocked at predetermined intervals. The cam 102 is secured as by bolts 45 to one of a pair of spaced apart supporting frame members 103 and 104 in which the cylinder shaft 36 is journaled as by ball bearings 105. Rotation of the cylinder 13 upon its bearings 105 will cause the shaft 98 to be rocked by the cam 102 which 50 is properly formed to cause the above described actuation of the valve parts to hold a sheet upon the cylinder 13 after it has been engaged against the stops 43.

55 Spaced apart arms 106 and 107, one being located on either side of the arm 97, are secured to the rock shaft 98 (see Figures 4, 8 and 14). The arms 106 and 107 carry cam members 108, 109 on their respective free ends. The camming edges 111 and 112 of the members 108 and 109 respectively are each engaged by a roller 113 which is journaled in a bracket 114 secured upon the end of each of the adjacent slides 53. The camming edges 111 and 112 are oppositely formed 65 whereby rocking movement of the shaft 98 will cause the slides 53 to be oppositely moved away from each other.

70 Due to their unequal overlap, the valve members will be slightly moved before the valve ports are completely opened. As soon as the valve has established a connection between a source of vacuum such as a vacuum pump and the movable slides 53, the sheet will be pressed by atmospheric pressure against the peripheral surface 75 of the cylinder. By having fewer openings 62

open or active, the sheet moving force of one bar, 48 or 49, will overbalance that of the other, and the counteracting force of the bar having the least number of openings 62 active, will impose a strain on the sheet and cause it to be 5 straightened and stretched taut when the camming members 108 and 109 are actuated.

The arrangement shown is such that fewer openings 62 are in connection with the source of vacuum in the bar 49 than are so connected 10 in the bar 48, this being made possible by the structure of the stems 57 as above described, so that the sheet moving force of the bar 48 will overbalance that of the bar 49, whereby the separating movement of these bars by the cam 15 members 108 and 109 will cause the sheet to be slipped laterally, or lengthwise along the cylinder 13, up against a stop bar 115 (see Figures 2, 3, 7 and 12). The bar 115 is secured, as by screws, in a predetermined position upon and 20 extended between a pair of spaced apart inverted T shaped bars 116 and 117 (Figures 12 and 13) slidably mounted in suitable slots 120, in gibs 52 and 51 respectively, one T shaped bar being disposed on either side of the bar 48. Similar 25 inverted T shaped bars 118 and 119 are provided in the gibs 51 and 52 (see Figure 2) and disposed one on either side of the bar 49 should it be desirable to stop the sheet in an opposite direction against a stop bar associated with the 30 bar 49. A plurality of spaced screw receiving threaded openings 121 are provided in all of the T shaped bars and these openings are properly disposed to permit the location of the stop bar 115 in proper position to transversely centralize 35 the sheet upon the cylinder 13 and to laterally register it with the impressions to be printed thereon.

The slides 53, with the respective brackets 114 secured thereto, are each constantly urged in a direction to insure constant contact of the roller 113, journaled in each bracket against the respective cam member 108 and 109 by a spring 122 (see Figure 4). Each spring reacts between the respective bracket 114 and a plate 123 secured to each of the supporting discs 71 and 73. The inverted T shaped bars 118, 119 are constantly urged outwardly toward the respective end of the cylinder by springs 124, one reacting between the inner end of each T bar and the 50 end of the respective slot 120 in the gibs 51 and 52 (see Figure 12).

While the adjustment of the stop bar 115 along the cylinder 13 is roughly made by use of the screw receiving threaded openings 121 a fine 55 adjustment is made possible by the provision of a threaded rod 125 in cooperation with a threaded opening in the outer ends of each T shaped bar 118, 119 (see Figures 7 and 12). The outer ends of each of the rods 125 has a pinion 60 secured thereto and the teeth of these pinions are in mesh with the teeth of a gear 127 journaled to an end plate 128. A tool engaging member or nut 129 is secured to each gear 127 whereby it may be rotated to actuate the rods 65 125 and thereby simultaneously slide the T shaped bars 116 and 117 or 118 and 119 against the springs 124 to delicately position the stop bar 115 connected thereto.

Sheet gripping device and carrier

70 Each of the sheet gripper devices provided on the endless chains 14 include an elongated tube 131 which extends between and are secured to, holders 132 and 133, one holder being suitably 75

connected to each of the chains, which in turn are led over and driven by a sprocket 134 secured to the shaft 36 at each end of the cylinder 13 (see Figures 2, 3, 4 and 5). A smaller diameter tube 135 (see Figures 9 and 10) is disposed concentrically to, and in, the tube 131 and also extends across the cylinder 13. The tube 135 is arranged to be rotatable relatively to the tube 131. A plurality of fingers 136 are secured to 10 the outer tube 131 and are spaced apart lengthwise thereof to agree with spaced apart fingers 137 secured to the inner tube 135. The fingers 137 pass through suitable openings 138 in the outer tube and are constantly urged into closed 15 engaging position with the fingers 136 by springs 139.

Each of the holders 132 and 133 are provided with a pair of rollers 141 and 142, the roller 141 being journaled in and between spaced apart 20 links 143 which are pivoted to the holders 132 and 133 at 144, and the roller 142 being journaled to the respective holder at 145 (see Figures 6 and 10). Another roller 146, herein shown of larger diameter than the rollers 141 and 142, 25 is journaled to the holders 132 and 133 substantially midway between the rollers 141 and 142. The rollers 146 are adapted to ride on arcuately shaped two piece guides, portions 147 and 148 constituting one guide and located at one 30 end of the cylinder 13 and portions 149 and 151 constituting the other guide and being located at the other end of the cylinder. Each of the portions 147 and 148 of one guide are pivoted on eccentric studs 152 and 153 respectively to the adjacent machine frame 103 and the portions 35 149 and 151 are pivoted on similar eccentric studs 152 and 153 respectively to the adjacent machine frame 104.

The guide portions 147 and 149 are adjustable 40 toward and away from the axis of the cylinder 13 by means of their eccentric pivot stud 152 and by an adjusting screw 154, shown only in connection with guide 149, secured in the adjacent frame and being adapted to engage the free end of each portion. The guide portions 45 148 and 151 are resiliently positioned by springs 155 which react between a shoulder formed at the free end of each guide portion and a screw 156 adjustably secured in the adjacent frame. Stop screws 157 adjustably secured to the adjacent frame limit the inward movement of the guide portions 148 and 151 and the engagement of interengaging abutting ends of the guide portions 147 and 148 and 149 and 151 between the eccentric studs 152 and 153 limit the inward 55 movement of the portions 147 and 149.

The arrangement of the above parts is such that the rollers 146 on each holder 132 and 133 cooperates with the guides 147, 148, 149 and 151 60 respectively, the said guides extending more than 180° and being substantially concentric with the axis of the cylinder 13 and disposed above the same, to press the sheet gripping devices inwardly to cause engagement of the rollers 141 and 142 on each holder 132 and 133 with the ends of a pair of plates 158 and 159 respectively. The plates 158 and 159 are secured to the inner face of each of the sprockets 134, that is, the faces thereof adjacent the cylinder end, one 65 plate 158 of each pair being provided with a square end and the end of the other plate 159 of each pair being formed to provide a seat to receive the engaging roller. One of the plates 158 is provided with an arcuate seat 161 while 70 the other has a V shaped seat 162. The plate 75

158 having the V shaped seat 162 also has the edges of the V seat beveled as at 163 to fit a V shaped groove 164 provided in the periphery of the cooperating roller 142 (see Figure 3). This arrangement insures both peripheral 8 and transverse register of the sheet gripping devices with the cylinder 13, each device as it approaches the cylinder being pressed into a suitable recess formed by cutting away the outer shell 78 of the cylinder and sections of each disc 10 88, 89 and 71-75 to permit entrance of the device therein. Suitably formed plates 165 (see Figures 4 and 9) are provided and secured to each of the intermediate discs 71 and 73 to support roller 170 adapted to engage the outer tube 15 131 and cause deflection of the tube outwardly so that the deflection due to centrifugal force will be anticipated and the tube be held steady.

An arm 166 secured to the inner tube 135 extends outwardly through an opening 167 provided in the holder 133 and has a roller 168 journaled therein (see Figures 5, 9 and 10). The roller 168 is adapted to engage the inner edge of an arcuate plate cam 169 supported on brackets 171 to the adjacent frame member 104. 20 The arm 166 when engaged by the cam plate 169 rocks the tube 135 and opens the gripper fingers by causing swinging movement of the fingers 137 away from the fingers 136. The cam plate 169 is also disposed generally concentric with the axis of the cylinder 13 and extends somewhat less than 180° thereover. The camming edge 172 of the cam plate 169 is formed to gradually open and close the fingers 136 and 137 and to insure that they are fully open substantially over the middle portion of the plate 169. The plate is so disposed relatively to the cylinder 13 that the fingers 136 and 137 will be fully closed upon a sheet carried by the cylinder before the chains 14 carrying the gripping devices ride off of the respective sprockets 134 and before the rollers 146 are released from the action of the guide portions 147 and 149 to insure that the sheet, now in register on the cylinder, will be transferred therefrom by the chain 14 45 and along with the gripping devices, to and in perfect register with, the printing units 15-18 inclusive.

Misplaced or absent sheet detecting

The sheet feeding and registering mechanism of this invention is provided with means acting automatically to set the printing unit tripping roller 26 in an operable position should a sheet be misplaced upon, or be absent from, the cylinder 13. The roller 26 setting means has associated with it means to strip a misplaced sheet from the cylinder, and from the gripping fingers 136 and 137, to prevent it being carried to a printing unit. Both the roller setting means 60 and the sheet stripping means are set in operable position by the detection of a sheet being misplaced or absent from the cylinder 13 by levers 173 and 174, a pair of which are herein shown in Figure 4 spaced apart lengthwise of 65 the cylinder 13 and disposed one adjacent the disc 71 and the other adjacent the disc 73. The stops 43 are replaced at these points with a pair of elongated stops 175 and 176, one of which is disposed on either side of each of the levers 70 173 and 174.

The levers 173 and 174 (see Figures 4 and 9) are formed with a narrow body portion 177 having a substantially wider head portion 178 at its outer end and has a cross bar 179 secured to its 75

inner end. The levers 173 and 174 have a spindle 181 secured to their body portions 171, which spindle has its ends journaled in the stops 175 and 176. The levers 173 and 174 are preferably formed from sheet metal so as to be as light in weight as possible and both the cross bar 179 and the spindle 181 are brazed or similarly secured thereto. The wider outer end, or head portion 178, is adapted to freely pass between the outer ends of the stops 175 and 176 and is urged beyond the surface of these stops 175 and 176, and of the stops 43 toward the sheet being fed onto the cylinder, by a small leaf spring 182, a sufficient amount to be engaged by the edge of this sheet before it engages the said stops. The leaf spring 182 has one of its ends secured to the cylinder 13 while its other end engages the respective lever 173 or 174.

Normally each of the cross bars 179 are maintained by the springs 182 in the path of a stop plate 183 secured upon the free end of each of a pair of arms 184, which are secured to a rock shaft 185 (see Figure 9). The shaft 185 extends from the lever 173 through the discs 71, 72, 73, 74 and 75 to the right hand end of the cylinder 13. When a sheet has been fed onto the cylinder into proper engagement with the stops 43, 175 and 176, the levers 173 and 174 are swung into alignment with these stops against the tension of the springs 182, whereby the cross bars 179 are moved out of the path of the plates 183 thereby permitting movement of the arms 184, and consequently rocking movement of the shaft 185. Thus the proper disposition of a sheet upon the cylinder 13 and against the stops 43, 175 and 176 is detected. Any sheet which is misplaced on the cylinder, whereby its forward edge is not in engagement with all of the stops 43, 175 and 176 will be detected, as in such cases one or the other of the levers 173 and 174 will not be swung to carry the cross-bar 179 thereon out of the path of one of the stop plates 183, and thus rocking movement of the shaft 185 is prevented. In like manner, absence of a sheet from the cylinder 13 will cause failure of both of the levers 173 and 174 to swing to carry the cross-bars 179 out of the path of the plates 183.

When the shaft 185 is prevented from rocking, due to the failure of either or both of the cross-bars 179 to be moved out of the path of the plates 183, a roller 186, journaled in the free end of an arm 187 which is secured to the end of the shaft 185 adjacent the right hand end of the cylinder 13 and disposed beyond the sprocket 134 thereat, is prevented from following down the camming edge 188 of a plate cam 189 which is secured, as by screws, to the frame 104 (see Figure 5). Another roller 191, also carried by the arm 187, is therefore prevented from moving out of the path of a long arm 192 of a cam lever 193 which is pivoted at 194 (see Figure 10) to the frame 104 and engages the lever to rock it on its pivot 194 as the cylinder 13 rotates. The short arm 195 of the lever 193 (see Figure 10) is connected by a link 196 to an arm 197 pivoted at 198 to an arm 199 secured to a rock shaft 201. The shaft 201 extends from one frame 103 to the other frame 104, being journaled at each end in each frame. The shaft 185 is constantly urged to rock in the proper direction to cause the roller 186 to follow the cam edge 188 by a spring 180, which reacts between an arm 190 on the shaft 185 and a stud 200 (see Figures 5 and 9) secured to the disc 74. A coiled spring 202 (see Figure 10) is provided to normally maintain the lever 193 in its roller 191

engaging position by reacting between a lug 203 on the frame 104 and a stud 204 pivoted on the free end of the lever short arm 195.

The spring 202 acting on the lever short arm 195 also maintains a catch pin 205, provided on the free end of the arm 197 out of proper position to be engaged by a catch 206 carried by a bifurcated arm 207 secured upon one end of a short-shaft 208 journaled in the frame 104 (see Figures 5 and 10). Another arm 209, secured upon the other end of the shaft 208, carries a roller 210 which rides upon the camming edge 212 of a plate cam 213. The cam 213 is secured upon the hub 214 of the large bevel gear 38, secured upon the end of the cylinder shaft 36. A coiled spring 215 reacting between an arm 216 secured on the shaft 208 and a stud 217 connected to the frame 104 maintains the roller 210 in constant contact with the cam 213 whereby the shaft 208 is being continuously rocked to swing the catch 206 to and fro. The catch 206 will engage the pin 205 when the latter is lowered, due to the downward swinging of the arm 197 through the link 196 by swinging movement of the lever 193 induced by the engagement of the roller 191 with the long arm 192 of said lever. Engagement of the pin 205 by the catch 206 will, through the arm 197, cause the arm 199 to be rocked to rock the shaft 201.

Rocking movement of the arm 199 as herein shown, toward the cylinder 13 (see Figure 10) will, as above described, rock the shaft 201 whereby an arm 218 secured upon the end of said shaft adjacent the frame 104 will be rocked to present a cam block 219 carried thereby in position to be engaged by the roller 168, carried by the holder 133, whereby the sheet gripping fingers 136 and 137 will be opened to release a sheet, should one be gripped thereby. At the same time the fingers 136 and 137 open, a plurality of stripper 40 fingers 221 of a form as shown in Figure 2 and in dotted lines in Figure 10 and which are spaced apart along the shaft 201 and connected thereto, as by screws at their lower ends, are swung toward the cylinder 13 to become disposed beneath the sheet, if any, being carried by said fingers to strip such sheet from both the fingers and the cylinder. The rocked shaft 201, the arm 199, the cam block 219 and the stripper fingers 221 are returned after actuation as above described and are normally maintained, unless so actuated, by coiled springs 222 reacting between a lug 223 on the frames 103 and 104 and arms 224 secured to the shaft 201.

Printing unit tripping arrangement

Referring back to the roller 26 on the gripper device and which as described is adapted when properly set to trip the cylinders of the printing units as it passes thereby, a sleeve 225 is provided which is rotatably mounted upon the outer tube 131 and has a plurality of pairs of spaced apart ears 226, 227, 228 and 229, and to and between each pair of ears, rollers, 26, 231, 232 and 233 are respectively disposed and journaled (see Figures 3, 6 and 11). A spring pressed pin 234 cooperates with the roller 231 to maintain the sleeve 225 in either of its rotative positions to which it may be moved relatively to the tube 131. The rollers 231 and 232 are axially spaced from the rollers 26 and 233, with the roller 232 disposed to engage a cam block 235 mounted on an arm 236 connected to the shaft 201.

The arrangement is such that when a gripping device passes the cam block 235 and said cam

block has been rocked inwardly toward the cylinder 13 due to the rocking movement of the shaft 201 as above described, the sleeve 225 will be rotated about the tube 131, as shown in dotted lines in Figure 11. The roller 231 will then be disposed on the other side of the pin 234 and the roller 26 will be disposed outwardly a sufficient amount to insure it engaging with the actuating and control finger 27 of the tripping mechanism 25 at each printing unit, to actuate the same to prevent the printing cylinders engaging. After the sheet gripping device, so set, has passed by the sheet receiving device 28 a suitable cam block or the like (not shown), but suitably positioned to engage the roller 233, will reset the sleeve 225 into its normal position wherein it will be maintained by the cooperating pin 234 and the roller 231. Suitable chain guides 237 are provided at each end of the cylinder 13 to be engaged by and to brace the chain 14 passing thereby, whenever the cam blocks 219 and 235 are disposed to open the gripper fingers 136 and 137 and to rock the sleeve 225 respectively, as above described.

Provision is made of means to manually actuate the lever 193 to set the printing unit tripping roller 26 and to strip a sheet from the cylinder 13. This means includes a link 238 connected to the lever 193 at 239 (see Figure 10) and to a lever arm 241 secured to a stud shaft 242, which extends through the frame 104 and has a handle 243 secured thereto. Suitable actuation of the handle 243 will cause the above mentioned actions to take place.

Operation

The detail operations of the several portions of the sheet feeding and registering mechanism of this invention have been described in connection with the above description of the parts thereof. The sequence in which these operations are performed by the mechanism is controlled by the controlling and actuating cams 102, 108, 109, 169, 189 and 213 together with the gear and chain 40 drives associated with the various parts, the cams being formed and driven in timed relation with the endless chain 14, carrying the sheet gripping mechanisms, and with the drive gears 38, 39, 35, 34 and 44. As referred to above, the sheets are fed one at a time by suitable means, including the endless tapes 31 and cooperating sheet pushing members 40, and are driven slightly faster than the cylinder 13, upon and along 45 the guide plate 41, which directs the sheets upwardly upon the cylinder 13 beneath the endless tapes 42. The feeding of the sheets upon the cylinder 13 is timed by suitable gear connections 34, 35 and 44 so that the forward edge of the sheet reaches the cylinder in time to engage 50 against the stops 43, and due to the faster rate of speed of the tapes 42 is constantly urged thereagainst.

As the cylinder 13 is continuously rotating, the 55 sheet edge, firmly pressed against the stops 43, moves forward with the cylinder, and at the same time one of the plurality of sheet gripping devices carried on the endless chain 14 is in the recess provided therefor in the cylinder, and is 60 directly in advance of the stops 43, with the sheet gripping fingers 136 and 137 thereof in open position, the roller controlling the finger 137 having become engaged by the plate cam 169. The sheet gripping devices are also being held in this recess 65 by the engagement of the large rollers 146 with

the guides 147, 148, 149 and 151 and being accurately located on the cylinder by the cooperating beveled edges 163 of the V shaped seat 162 and grooves 164 in the plate 159 and the roller 142 respectively.

As soon as the cylinder 13 has advanced sufficiently for the sheet to overlie the sheet holding bars 48 and 49, the valve plate 89 is rotated by the cam 102 to connect the openings 56 with the vacuum pump (not shown), the bars 48 and 49 10 slightly subsequent to this action, being started to slide in opposite directions by the camming members 108 and 109. Pressure now being applied to the sheet to hold it upon the bars 48 and 49, more firmly to one than to the other, causes 15 the sheet to be slipped transversely, or axially in respect to the cylinder 13, to engage one of its edges against the stop bar 115. Continued rotation of the cylinder 13 advances the sheet held thereon by the tapes 42 against the stops 43, and by air pressure upon the bars 48 and 49 which in turn, due to their oppositely directed movements have drawn the sheet taut with one edge 20 engaging the stop bar 115, to a position whereat the fingers 137 are released from the opening 25 action of the cam 169 and they close with the fingers 136 to firmly grip a sheet therebetween.

The sheet, now accurately in register, is carried along by the sheet gripping mechanism in 30 timed relation, due to the chain drive 14, which has meanwhile followed over the sprockets 134, and is driven thereby, due to their connection with the bevel gears 38 and 39, to the printing units 15—18, with which the vertical bevel gear 35 shaft 37 is connected in the usual manner. As the sheets pass through the printing units, impressions in color may be printed thereon with the different color from each printing unit being accurately in register with the others. After 40 passing the last printing unit 18, the printed sheet may be transferred to the delivery belt or chain 29 and deposited at the receiving device 28.

Should the detector fingers detect the absence 45 of a sheet or the presence of a sheet misplaced, or improperly in engagement with the stops 43, the cams 189, 193 and 213 are automatically brought into action to open the fingers 136 and 137, to strip the misplaced sheet from the cylinder 13, and to set the roller 26 in position to trip the mechanism 25 at each printing unit, to prevent the printing cylinders from contacting, while the sheetless sheet gripping mechanism passes thereby, all as above described in 55 the above description of the parts thereof.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in, or possessed by, the mechanism herein disclosed forms a part 60 of the invention included in this application.

What I claim is:

1. In a sheet feeding and registering mechanism for a printing machine, a continuously rotating cylinder, means to feed a sheet to said cylinder, a stop on said cylinder against which the forward edge of the sheet is pressed by said feeding means, a stop bar on said cylinder adjacent one of its ends, sheet holding means slidable axially of said cylinder to press a side edge 75

of the sheet against said stop bar, sheet gripping fingers moving with the cylinder to grip the forward edge of the sheet, and a carrier upon which said fingers are mounted to carry the finger gripped sheet from said cylinder.

5. In a sheet feeding and registering mechanism for a printing machine, a continuously rotating cylinder, means to feed a sheet to said cylinder, a stop on said cylinder against which the forward edge of the sheet is pressed by said feeding means, a stop bar on said cylinder adjacent one of its ends, sheet holding means slideable axially of said cylinder to press a side edge of the sheet against said stop bar, a sheet gripping and carrying device having sheet gripping fingers, and members on said cylinder and engageable by said device to locate it relatively to said cylinder and to the sheet thereon.

3. In a sheet feeding and registering mechanism for a printing machine, a continuously rotating cylinder, means to feed a sheet to said cylinder, a stop on said cylinder against which the forward edge of the sheet is pressed by said feeding means, a stop bar on said cylinder adjacent one of its ends, sheet holding means slideable axially of said cylinder to press a side edge of the sheet against said stop bar, a misplaced or absent sheet detector associated with said stop, operable sheet gripping fingers, and cooperating members between said fingers and said detector and actuated by said detector to open said fingers.

4. In a sheet feeding and registering mechanism for a printing machine, a continuously rotating cylinder, means to feed a sheet to said cylinder, a stop on said cylinder against which the forward edge of the sheet is pressed by said feeding means, a stop bar on said cylinder adjacent one of its ends, sheet holding means slideable axially of said cylinder to press a side edge of the sheet against said stop bar, a sheet printing unit having a control finger, a misplaced or absent sheet detector associated with said stop, a sheet gripping and conveying device, and a control finger tripping member on said sheet conveying device adapted to be set by said detector, to trip said control finger.

5. In a sheet feeding and registering mechanism for a printing machine, a continuously rotating cylinder, means to feed a sheet to said cylinder, a stop on said cylinder against which the forward edge of the sheet is pressed by said feeding means, a stop bar on said cylinder adjacent one of its ends, sheet holding means slideable axially of said cylinder to press a side edge of the sheet against said stop bar, a sheet gripping and carrying device having sheet gripping fingers, members on said cylinder and engageable by said device to locate it relatively to said cylinder and to the sheet thereon, a misplaced or absent sheet detector associated with said stop, and cooperating members between said fingers and said detector and actuated by said detector to open said fingers.

6. In a sheet feeding and registering mechanism for a printing machine, a continuously rotating cylinder, a sheet stop against which a sheet fed to said cylinder will engage, a sheet gripping device on said cylinder in advance of said sheet stop, a sheet holding device on said cylinder to the rear of said sheet stop, said sheet holding device including oppositely movable sheet holding members adapted to move axially of said cylinder, and a continuously running belt to engage a sheet and constantly press it against

said stop while said sheet holding device is in operation.

7. In a sheet feeding and registering mechanism for a printing machine, a continuously rotating cylinder, a sheet stop against which a sheet fed to said cylinder will engage, a sheet gripping device on said cylinder in advance of said sheet stop, a sheet holding device on said cylinder to the rear of said sheet stop, said sheet holding device including oppositely movable sheet holding members adapted to move axially of said cylinder, a cam to move each sheet holding member to draw a sheet taut axially of said cylinder, a stop bar adjacent an end of said cylinder, said sheet holding members being adapted to draw an edge of a sheet against said stop bar, and a continuously running belt to press another edge of the sheet against said stop.

8. In a sheet feeding and registering mechanism for a printing machine, a continuously rotating cylinder, a sheet stop against which a sheet fed to said cylinder will engage, a sheet gripping device on said cylinder in advance of said sheet stop, a sheet holding device on said cylinder to the rear of said sheet stop, said sheet holding device including oppositely movable sheet holding members adapted to move axially of said cylinder, a continuously running belt to engage a sheet and constantly press it against said stop while said sheet holding device is in operation, a sheet edge engaging member associated with said stop, and a sheet stripping member adapted to be actuated by said sheet edge engaging member to strip a misplaced sheet from said cylinder.

9. In a sheet registering mechanism, a rotating cylinder having a sheet edge engaging stop thereon, a running belt to press a sheet against the cylinder and an edge of the sheet against said stop, a member operable to strip a sheet from said cylinder, and a member to actuate said sheet stripping member controlled by a sheet pressed toward said stop by said belt.

10. In a sheet registering mechanism, a rotating cylinder having a sheet edge engaging stop thereon, a running belt to press a sheet against the cylinder and an edge of the sheet against said stop, sheet gripping members associated with said cylinder including closable and openable sheet gripping fingers, a member operable to strip a sheet from said cylinder after it has been gripped by said fingers, and a member to open said fingers and to actuate said sheet stripping member controlled by a sheet pressed toward said stop by said belt.

11. In a sheet registering mechanism, a rotating cylinder having a sheet edge engaging stop thereon, a running belt to press a sheet against the cylinder and an edge of the sheet against said stop, a stop bar disposed on and adjacent an end of said cylinder, sheet holding members operable to slippingly hold a sheet and to press an edge thereof against said stop bar, sheet gripping members associated with said cylinder including closable and openable sheet gripping fingers, a member operable to strip a sheet from said cylinder after it has been gripped by said fingers, and a member to open said fingers and to actuate said sheet stripping member controlled by a sheet pressed toward said stop by said belt.

12. In a combined sheet transferring and registering cylinder, means to rotate said cylinder, a stop on said cylinder to engage the forward end of a sheet feed onto said cylinder, a stop bar on and adjacent to one end of said cylinder, sheet holding means associated with said stop bar and

- adapted to press a side edge of the sheet there-
against, sheet gripping fingers mounted on a car-
rier, said carrier being adapted to rotate about
the axis of and with said cylinder a portion of
one revolution of said cylinder, and cooperating
members associated with said cylinder to regis-
ter said carrier with said stop while said carrier
is rotating with said cylinder.
13. In a combined sheet transferring and reg-
istering cylinder, means to rotate said cylinder,
a stop on said cylinder to engage the forward
end of a sheet fed onto said cylinder, sheet grip-
ping fingers mounted on a carrier, said carrier
being adapted to rotate about the axis of and
with said cylinder a portion of one revolution
of said cylinder and then to convey a sheet away
from said cylinder, and cooperating members as-
sociated with said cylinder to register said carrier
with said stop while said carrier is rotating with
said cylinder.
14. In combination, a rotating cylinder, a plu-
rality of stops disposed in alignment axially
across said cylinder, a running belt adapted to
feed a sheet onto said cylinder and an edge of the
sheet against said stops, a stop bar adjacent
one end of said cylinder, oppositely movable sheet
holding members adapted to maintain another
sheet edge against said stop bar, sheet gripping
mechanism adapted to be associated with said
cylinder during a portion of one revolution of said
cylinder, and cooperating members between said
mechanism and said cylinder to register said
mechanism with the sheet as held against said
stops and said stop bar.
15. In combination, a rotating cylinder, a plu-
rality of stops disposed in alignment axially
across said cylinder, a running belt adapted to
feed a sheet onto said cylinder and an edge of
the sheet against said stops, a stop bar adjac-
ent one end of said cylinder, oppositely movable
sheet holding members adapted to maintain an-
other sheet edge against said stop bar, sheet grip-
ping mechanism adapted to be associated with
said cylinder during a portion of one revolution
of said cylinder, said mechanism having a mem-
ber adapted to be set in position to operate a
trip mechanism associated with a printing unit to
which said sheet gripping mechanism is carried
after leaving said cylinder, means acted upon by
the sheet to prevent said member becoming set
in trip mechanism actuating position, and co-
operating members between said mechanism and
said cylinder to register said mechanism with the
sheet as held against said stops and said stop bar.
16. In combination, a rotating cylinder, a plu-
rality of stops disposed in alignment axially
across said cylinder, a running belt adapted to
feed a sheet onto said cylinder and an edge of the
sheet against said stops, sheet gripping mech-
anism adapted to be associated with said cylin-
der during a portion of one revolution of said
cylinder, cooperating members on said cylinder
and on said mechanism to register said mech-
anism with said stops, said mechanism having a
member adapted to be set in a position to actu-
ate a trip mechanism at a position remote from
said cylinder, means acted upon by the sheet
edge against said stops to prevent the setting of
said member, and cooperating members between
said sheet gripping mechanism and said cylin-
der to register said sheet gripping mechanism
with the sheet as held against said stops and said
stop bar.
17. In a printing machine having an impres-
sion cylinder, sheet feeding means including a
- rotatable sheet registering cylinder having an
opening in its periphery, sheet gripping mecha-
nism adapted to rotate with said registering cyl-
inder while disposed in the opening therein and
to carry the sheet from the cylinder, sheet stops
arranged to be engaged by a sheet fed to said
registering cylinder whereby the sheet will be
registered in respect to said sheet gripping mech-
anism, and means to actuate said sheet gripping
mechanism after a sheet is against said stops. 16
18. In combination with a printing machine,
sheet feeding means including a rotatable sheet
registering cylinder having an opening in its pe-
riphery, a plurality of sheet gripping mechanisms
adapted to rotate with said cylinder while being 15
successively disposed in the opening and to carry
sheets therefrom to a printing cylinder, sheet
stops arranged to be engaged by each sheet fed
onto said registering cylinder whereby the sheet
will be registered in respect to said sheet gripping
mechanism, means to actuate each sheet gripping
mechanism after a sheet is against said stops, and
means to detect the failure of a sheet to engage
said stops and to prevent the sheet being carried
from said cylinder by said gripper mechanism. 25
19. In combination with a printing machine,
a flexible sheet conveyor and a rotatable cylinder
having an opening in its periphery, sheet grip-
ping mechanism carried by said conveyor and re-
ceivable in the cylinder opening, means to regis-
ter and secure said mechanism in the opening
while the cylinder is rotating, sheet registering
stops adapted to be engaged by a sheet received
on said cylinder, and sheet feeding means adapt-
ed to feed a sheet to said cylinder and hold it 30
against said stops before said sheet gripping
mechanism is actuated to grip the sheet.
20. In combination with a printing machine,
a flexible sheet conveyor and a rotatable cylinder
having an opening in its periphery, sheet gripping 40
mechanism carried by said conveyor and receiv-
able in the cylinder opening, means to register
and secure said mechanism in the opening while
the cylinder is rotating, sheet registering stops
adapted to be engaged by a sheet received on
said cylinder, sheet feeding means adapted to
feed a sheet to said cylinder and hold it against
said stops before said sheet gripping mechanism
is actuated to grip the sheet. 45
21. A rotatable sheet receiving and registering 50
cylinder adapted for disposition between a sheet
feeding mechanism and a printing unit of a print-
ing machine, said cylinder having an opening to
receive a sheet gripping mechanism carried
thereabout by a conveyor and having means to 55
register said gripper mechanism thereon, and
stops carried by said cylinder to be engaged by
a sheet to register it peripherally and axially on
said cylinder before said gripper mechanism is
actuated to grip the sheet.
22. A rotatable sheet receiving and registering
cylinder adapted for disposition between a sheet
feeding mechanism and a printing unit of a print-
ing machine, said cylinder having an opening to
receive a sheet gripping mechanism carried there-
about by a conveyor and having means to register 70
said gripper mechanism thereon, stops carried by
said cylinder to be engaged by a sheet to register
it peripherally and axially on said cylinder before
said gripper mechanism is actuated to grip a 75

sheet, and a sheet register detector mechanism carried by said cylinder in association with one of said stops and adapted to cause actuation of a device to release a sheet from said gripper mechanism as it leaves said cylinder.

23. In combination with a printing machine having a printing cylinder tripping mechanism associated with one of its printing units, a sheet feeding and registering cylinder having means to receive and register a sheet gripping mechanism, a sheet gripping mechanism, a conveyor adapted to carry said sheet gripping mechanism from said cylinder to said printing unit, a tripping member carried by said gripping mechanism, means on said cylinder to set said tripping member in position to actuate said printing cylinder tripping mechanism as said member approaches the same, means on said cylinder to register a sheet disposed thereon, and a sheet register detecting member on said cylinder actuated by a sheet received thereon to prevent the setting of said tripping member in tripping position.

24. In a printing machine, a rotating cylinder, sheet grippers moving therewith and operable to grip a sheet fed to said cylinder, means to feed a sheet to said cylinder at a higher speed than the peripheral speed thereof, a side registering stop positioned to register a side edge of the sheet on the cylinder, sheet moving means on the cylinder to move the sheet against the stop, and means to actuate the grippers to engage the sheet after the sheet has been moved against the stop.

25. In a printing machine having an impression cylinder, a sheet registering cylinder having sheet grippers moving therewith and operable to grip a sheet fed to said registering cylinder and to carry the sheet from the registering cylinder, means to feed a sheet to said registering cylinder at a higher speed than the peripheral speed thereof, a plurality of sheet registering stops positioned to register the forward edge of the sheet on the registering cylinder, sheet moving means operating faster than the peripheral speed of the registering cylinder to move the sheet against the stops, and means to actuate the grippers to engage the sheet after the sheet has been moved against the stops.

26. In a printing machine having an impression cylinder, a sheet registering cylinder having a sheet gripping member carried by said registering cylinder as it rotates and being operable to grip a sheet disposed on said registering cylinder and to carry the sheet from the registering cylinder, means to feed a sheet to the registering cylinder, a sheet registering stop carried by said registering cylinder, sheet moving means to move the sheet against said stop, and means to actuate said sheet gripping member after a sheet has been moved against the stop.

27. In a printing machine, a rotatable cylinder, a sheet gripping member carried by said cylinder as it rotates and being operable to grip a sheet disposed on said cylinder and to carry the sheet from the cylinder, means to feed a sheet to the cylinder, a sheet registering stop carried by said cylinder for engaging the forward edge of the sheet, a sheet side registering stop carried by said cylinder, means to move the sheet forwardly against the forward stop and transversely against the side stop, and means to actuate said sheet gripping member to grip a sheet positioned against said stops.

28. In combination, a sheet registering cylinder and a sheet feeding member rotatable therewith, operable sheet gripping fingers carried by said

member, means to strip a sheet from said feeding member, and means to open said fingers and actuate said sheet stripping means when a sheet is misplaced in respect to said sheet feeding member.

5

29. In a sheet feeding mechanism, a sheet registering cylinder, releasable sheet engaging means rotatable with the cylinder and adapted to feed a sheet, and means to engage a sheet improperly disposed in respect to said sheet engaging means and to remove it from said mechanism.

30. In a sheet feeding mechanism, a sheet registering cylinder, releasable sheet engaging means rotatable with the cylinder and adapted to feed a sheet, means to engage a sheet improperly disposed in respect to said sheet engaging means and to remove it from said mechanism, and means actuated by a sheet properly disposed to prevent operation of said sheet removing means.

31. In a printing machine having a plurality of printing cylinders and means for tripping them "on" and "off" impression, a sheet feeder, a flexible sheet conveyor having a plurality of relatively spaced sheet carriers each adapted to receive a sheet, a rotating member about which the sheet conveyor runs and which is arranged to guide each sheet carrier successively past a position where it may receive a sheet from the feeder, said conveyor being arranged to convey the sheets successively past each printing cylinder, a sheet detector in the path of sheets presented to the sheet carriers and operable by a misregistered sheet, and means on the conveyor operated by said detector to actuate the tripping mechanism of each of the printing cylinders in succession, on the approach of a sheet carrier to which a misregistered sheet was presented.

32. In a printing machine having a plurality of printing cylinders and means for tripping them "on" and "off" impression, a sheet feeder, a flexible sheet conveyor having a plurality of relatively spaced sheet carriers each adapted to receive a sheet, a rotating member about which the sheet conveyor runs and which is arranged to guide each sheet carrier successively past a position where it may receive a sheet from the feeder, said conveyor being arranged to convey the sheets successively past each printing cylinder, a sheet detector associated with the said rotating member and operable by a misregistered sheet, and means on the conveyor operated by said detector to actuate the tripping mechanism of each of the printing cylinders in succession, on the approach of a sheet carrier to which a misregistered sheet was presented.

55

33. In a printing machine having a plurality of printing couples and means for tripping them "on" and "off" impression, a sheet feeder, a flexible sheet conveyor having a plurality of relatively spaced sheet carriers each adapted to receive a sheet, a rotating member about which the sheet conveyor runs and which is arranged to guide each sheet carrier successively past a position where it may receive a sheet from the feeder, said conveyor being arranged to convey the sheets successively through each printing couple, a sheet detector associated with the rotating member and movable to a first position in the presence of a misregistered sheet and to a second position by a properly registered sheet, and means on the conveyor operated by said detector when in the first position to actuate the tripping mechanism to trip "off" the impression of each of the printing couples in succession, on the approach of a sheet carrier to which a mis-

75

- registered sheet was last presented, and to actuate the tripping mechanism to trip "on" the impression of each of the printing couples in succession, on the approach of a sheet carrier to which a properly registered sheet was last presented.
34. In a printing machine having a plurality of printing couples, a sheet feeder, a flexible sheet conveyor having a plurality of relatively spaced sheet carriers each adapted to receive a sheet, a rotating member about which the sheet conveyor runs and which is arranged to guide each sheet carrier successively past a position where it may receive a sheet from the feeder, said conveyor being arranged to convey the sheets successively through each printing couple, a stripping device adjacent the conveyor and operable to divert a sheet from its normal path, a sheet detector in the path of sheets presented to the sheet carriers and operable by a misregistered sheet, and means on the conveyor operated by said detector to operate the stripping device, on the approach of a sheet carrier to which a misregistered sheet was presented.
35. In a sheet registering mechanism for a printing machine, a continuously rotating cylinder adapted to receive sheets, and means to register a sheet received by the said cylinder, including a sheet holding device carried by the cylinder and said holding device consisting of a member acting to hold the front edge of the sheet in front registry and adapted to move axially of the cylinder to adjust the sheet thereon, and to act as a retarding device to resist such movement of the sheet.
36. In a sheet registering mechanism for a printing machine, a continuously rotating cylinder adapted to receive sheets, and means to register a sheet received by the said cylinder, including a sheet holding device carried by the cylinder, the sheet holding device including oppositely movable sheet holding members adapted to pull unequally upon the sheet held thereby to move it in one direction axially on said cylinder while maintaining it taut.
37. In a printing machine having an impression cylinder, a sheet feeding device, a continuously rotating sheet receiving cylinder adjacent the sheet feeding device but spaced from the impression cylinder and adapted to receive a sheet from the sheet feeding device, sheet registering means on the sheet receiving cylinder, and a sheet engaging and transferring mechanism to remove the registered sheet from the sheet receiving cylinder and carry it to the impression cylinder.
38. In a printing machine having an impression cylinder, a sheet feeding device, a continuously rotating sheet receiving cylinder adjacent the sheet feeding device but spaced from the impression cylinder and adapted to receive a sheet from the sheet feeding device, sheet registering means on the sheet receiving cylinder, and a sheet engaging and transferring mechanism to remove the registered sheet from the sheet receiving cylinder and carry it to the impression cylinder and adapted to receive a sheet from the sheet feeding device, sheet registering means on the sheet receiving cylinder, and a sheet engaging and transferring mechanism to remove the registered sheet from the sheet receiving cylinder and carry it to the impression cylinder, the sheet engaging mechanism including a flexible carrier device wrapped about the sheet receiving cylinder and directed to the impression cylinder and having means to engage a registered sheet and transfer it from the sheet receiving cylinder to the impression cylinder.
39. In a sheet registering and transfer mechanism, a sheet receiving cylinder having sheet registering means thereon, and a sheet transfer device movable with and away from the cylinder and having a sheet gripping member adapted to grip a sheet registered on the sheet receiving cylinder and transfer it therefrom.
40. In a printing machine, a printing unit, a sheet receiving cylinder having a sheet registering stop thereon and being spaced from the printing unit, means carried by the sheet receiving cylinder to move a sheet axially thereon to position an edge of the sheet against the stop, and a sheet transferring device having a sheet engaging member thereon to transfer a registered sheet from the sheet receiving cylinder to the printing unit.
41. In a sheet registering mechanism for a printing machine, a continuously rotating cylinder adapted to receive sheets, and means to register a sheet received by the cylinder, including a sheet holding device carried by the cylinder, the sheet holding device including a member extending longitudinally of the cylinder and acting to hold the front edge of the sheet in front registered position and being movable axially on the cylinder and having a series of openings therein in connection with a source of vacuum whereby a sheet will be held downwardly against the cylinder by atmospheric pressure and in front and side registry by said member.
42. In a sheet registering mechanism for a printing machine, a continuously rotating cylinder adapted to receive sheets, and means to register a sheet received by the said cylinder, including a sheet holding device carried by the cylinder, the sheet holding device including members oppositely extending and movable axially on the cylinder, each of the members having a series of openings therein in connection with a source of vacuum, whereby a sheet will be held against the cylinder by atmospheric pressure, and means to vary the number of openings in each member which are connected to the source of vacuum.
